TUBE MAILING PACKAGE

Max Segel, 1105 Arbor Lane, Glenview, Ill. 60025

Filed Aug. 18, 1969, Ser. No. 18,735

Term of patent 14 years

Int. Cl. D9—04

U.S. Cl. D9—189

FIG. 1 is a perspective view of a tube mailing package showing my new design;

FIG. 2 is an end view thereof;

FIG. 3 is an end view thereof opposite that shown in FIG. 2;

FIG. 4 is a side view thereof;

FIG. 5 is the side view opposite of the view shown in FIG. 4;

FIG. 6 is a view taken along the line 6—6 of FIG. 3;

FIG. 7 is a view taken along the line 7—7 of FIG. 3;

FIG. 8 is a side view thereof of FIG. 2 with the lower half removed;

FIG. 9 is a side view thereof of FIG. 3 with the top half removed;

FIG. 10 is an end view thereof as seen from the left of FIG. 6;

FIG. 11 is an end view thereof as seen from the right of FIG. 6.

I claim:

The ornamental design for a tube mailing package, as shown.
